UNITED STATES PATENT OFFICE.

FRANK J. PAVELSKY AND FELIX F. MALODZIK, OF CUDAHY, WISCONSIN.

BLOCK-REFINISHER.

1,135,714.

Specification of Letters Patent. Patented Apr. 13, 1915.

Application filed July 20, 1914. Serial No. 851,895.

To all whom it may concern:

Be it known that we, FRANK J. PAVELSKY and FELIX F. MALODZIK, both citizens of the United States, and residents of Cudahy, in the county of Milwaukee and State of Wisconsin, have invented certain new and useful Improvements in Block-Refinishers; and we do hereby declare that the following is a full, clear, and exact description thereof.

10 The object of our invention is to provide a simple, economical and effective apparatus for refinishing the surfaces of butchers' blocks, the same being so constructed and arranged that a table is adjusted to one side 15 of the block upon the desired plane of the cut for initially supporting a self-contained motor driven cutter, the cutting face of the tool being upon the plane of the upper surface of the table, whereby the motor which 20 is arranged to float or slide upon the table can be shifted therefrom to the refinished surface of the block, which refinished surface forms, in conjunction with the table, an uninterrupted floor for the support of 25 said motor.

With the above objects in view the invention consists in certain peculiarities of construction and combination of parts as set forth hereinafter with reference to the accompanying drawings and subsequently claimed.

In the drawings Figure 1 represents an elevation of a block-finishing apparatus embodying the features of our invention, the same being shown partly in section, as indicated by line 1—1 of Fig. 2 and attached to a block to be refinished; Fig. 2, a sectional plan view of the same, the section being indicated by line 2—2 of Fig. 1, and Fig. 3, 40 an end view of the table mechanism with parts in section as indicated by line 3—3 of Fig. 1.

Referring by characters to the drawings, 1 represents a table which is, as shown, 45 adapted to have one edge arranged in abutting engagement with the block to be refinished, the upper surface of said table being adjusted upon the line of cut, as indicated. The table is provided with transversely disposed slotted ears 2, which ears project beyond the juxtaposed edges of said table and the slots thereof are arranged to receive draw bolts 3 provided with wing nuts 3', whereby the drawbolts are tightened. The inner hooked ends of the drawbolts have connected thereto chain or cable

stretches 4, the opposite ends of which stretches are adjustably connected to the hooked ends of drawbolts 5. These drawbolts are carried by a transversely disposed clamping bar 6, which bar is formed from two members bolted together and spaced apart to provide a continuous slot 6' through which the threaded shanks of the drawbolts 5 extend, the same being confined by thumb-nuts 5'. With this slotted arrangement of the draw-bar 6 and ears 2 which are connected to the table, the apparatus may be adjusted to different widths of blocks, it being understood that when either set of drawbolts are tightened that the connecting chain stretches will thus securely clamp the inner edge α of the table to the juxtaposed edge of the butcher's block. In order to provide a vertical support for the inner edge α of the table, its lower face has secured thereto a pair of depending ears 7, which ears carry pointed ended set-screws 7', the same constituting pins, the points of which are embedded into the block. Thus the inner edge 80 of the table is held against dropping downward under strain. The outer edge γ of the table is supported by a leg 8, which leg is secured to a post 9 by a clamping bolt 10 that extends through the post and through the slotted shank 8' of the leg, the said bolt being held by a binding nut 10'. Hence it will be seen that the leg may be adjusted as to length vertically to accommodate elevation of the table and to also finely adjust the upper surface of said table whereby it is maintained upon a horizontal plane, which plane constitutes a gage for the depth of cut in a refinishing operation of the block.

Owing to the fact that it is important to provide a fine adjustment for the upper surface of the table in order that it will assume a true horizontal plane and also to insure rigidity of the table in connection with the block, we provide the under surface of said table with depending bracket arms 11. These arms carry adjusting thumb screws 12 having feet 12' that engage the adjacent vertical surface of the block and by a slight manipulation of the thumb screws it is obvious that the upper surface of the table may be raised or lowered in which adjustment the pins 7' form fulcrum points. After the fine adjustment just mentioned has been effected, the table leg 8 is dropped to a position of engagement with the floor-line and thereafter firmly secured to the post by ma-

nipulation of the thumb-screw 10' in connection with the bolt 10. The table is provided for the purpose of initially supporting a motor A, which motor in this instance, is of 5 the electric type. The flanged base a of the motor is formed with three threaded apertures for the reception of threaded studs 13, the lower ends of which are rounded to form sliding supporting feet for the motor, where- 10 by the latter may be manipulated back and forth at the will of the operator, the said motor being provided with hand grips b to facilitate such manipulation. Hence it will be seen that the motor may be slid back and 15 forth upon the table in any direction.

The studs 13 are independently adjustable and form a three point contact, being held in their adjusted positions by set nuts 13'. This adjustment of the studs which consti- 20 tute feet for the motor is for the purpose of alining the cutting surface of a cutting tool 14 with the face of the table 1, it being im- portant that this alinement is true in order that the tool, when effecting a refinishing op- 25 eration, will true off the surface of the block upon the same plane as the surface of the table, whereby the refinished surface of said block will form a continuous ground upon which the feet of the motor may travel after 30 the initial refinishing operation. Hence the cutting tool is advanced and refinishes the block upon the same plane as the surface of the table. The cutting tool, as shown in Fig. 1, is detachably secured to a driven 35 spindle 15, which spindle is revolvably mounted in suitable bearings that extend from the head of the motor, the said spindle being in miter gear connection with the motor shaft. It should be understood that after the entire 40 surface of the block has been refinished in alinement with the surface of the motor- supporting table, the rotary cutting tool may be removed and a burnisher of any type sub- stituted therefor, whereby the refinished sur- 45 face may be smoothed down as finely as de- sired, the burnishing operation being similar to that described in connection with the cutting operation.

From the foregoing description it is ap- 50 parent that after the apparatus has been ad- justed to a block, as shown, the operator can readily shift the cutting tool carried by the

motor back and forth upon the table until such time as the surface of the block ad- jacent to the table is removed or finished 55 and, as the work progresses the operator shifts the motor from the table to the block which now forms a support. Thus the feet of the motor traveling over the finished block will at all time gage the depth of cut and 60 when the block has been entirely refinished its surface will be upon the plane of the sur- face of the table.

We claim:

1. A block refinishing apparatus comprising 65 a horizontally disposed table, means for attaching the same to one edge of the block, means for adjusting the table relative to the face of the block for gaging the depth of cut in a refinishing operation, a floating mo- 70 tor having supporting feet adapted to ini- tially rest upon the table, a cutting tool car- ried by the motor, the cutting face of which is disposed upon the same plane as the up- per surface of the table, whereby the block 75 is initially resurfaced to form a continuation of the table surface to permit the motor to travel from said table onto the block.

2. A block refinishing apparatus comprising 80 a horizontally disposed table, means for attaching the same to one edge of the block, means for adjusting the table relative to the face of the block for gaging the depth of cut in a refinishing operation, a floating motor having supporting feet adapted to initially 85 rest upon the table, means for adjusting the feet, a cutting tool carried by the motor, the cutting face of which is disposed upon the same plane as the upper surface of the table, whereby the block is initially resurfaced to 90 form a continuation of the table surface to 95 permit the motor to travel from said table onto the block.

In testimony that we claim the foregoing we have hereunto set our hands at Mil- 95waukee in the county of Milwaukee and State of Wisconsin in the presence of two witnesses.

FRANK J. PAVELSKE.
FELIX F. MALODZIK.
